UNITED STATES PATENT OFFICE

EUGENE R. SEITER, OF RIDGEFIELD PARK, NEW JERSEY, ASSIGNOR TO T. W. & C. B. SHERIDAN COMPANY, A CORPORATION OF NEW YORK

BOOKBINDING MACHINE

Application filed September 11, 1931. Serial No. 562,234.

This invention relates to bookbinding machines and more especially to mechanisms for applying backlining components to round back or other books in the process of manufacture thereof.

While the invention is applicable to various kinds and types of bookbinding machines, the disclosed embodiment of the present invention is of a design particularly adaptable to use in what is known as a backlining machine, wherein each of a succession of books is carried or advanced through the machine, preferably step-by-step-wise, and is treated successively by means for applying glue, means for applying a fibrous or crash lining piece, and means for applying a paper backlining thereover, the present embodiment being therein applicable between the steps of applying glue and paper lining to apply and register directly upon the glued back of the book headbands for the two ends thereof; although certain features can be used for applying a lining component consisting of combined headband and backlining, or a backlining paper without headband.

Specifically the present invention is illustrated in connection with a type of machine wherein the succession of books is moved along in a horizontal path, in a step-by-step manner, each book pausing at each place or station where an operation is to be performed, and the books standing with their rounded backs uppermost to receive the glue, and the various lining components including the headbands. Such type of backlining machine is illustrated in the patents of John Murray No. 982,438 of January 24, 1911, No. 1,263,273 of April 16, 1918, and No. 1,597,536 of August 24, 1926 to which reference may be made for various permissive details as to the guidance and feeding of the books, the gluing and lining applying mechanisms and the like.

A principal object of the present invention is to afford, in a bookbinding machine, a mechanism for applying headbands to books

which will be efficient and rapid in action, convenient in control, and accurate in the handling and placing of the headbands upon the book. A particular object is to afford a headbanding mechanism which will feed headband strip from one or two sources of supply, sever headbands therefrom, and apply the headbands directly to the glued ends of the backs of books standing with their backs exposed upwardly. A further object is to provide for the applying of headbands or other lining components to the books with a registering action accompanying the applying operation whereby the components are positioned accurately in relation to the ends of the book back. Other objects and advantages of the invention will be pointed out in the hereinafter following description of an illustrative embodiment thereof or will be understood to those skilled in the subject. To the attainment of such objects and advantages the present invention consists in the novel bookbinding machine or headbanding mechanism, and the novel features of combination, arrangement and operation herein illustrated or described.

Figure 1 is a front elevation of a portion of a bookbinding machine embodying the present invention, this view being taken from one lateral side of the machine, which will be termed the front side.

Fig. 2 is a corresponding elevation view taken from the other or back side of the machine.

Fig. 3 is a top plan view, with certain parts shown in section substantially on the horizontal line 3—3 of Fig. 1.

Fig. 4 is a right hand elevation, with certain of the longitudinal parts of the machine shown in transverse vertical section.

Fig. 5, on a larger scale than Fig. 4, is a right elevation with certain parts shown in section on the line 5—5 of Fig. 1.

Fig. 6 is a front elevation and section, taken on the line 6—6 of Fig. 5, with the book

broken away for condensation of the figure.

Fig. 7 is a right elevation and section taken on the line 7—7 of Fig. 6.

Fig. 8 is a top view and section taken on the line 8—8 of Fig. 6.

Fig. 9 is a front elevation of certain mechanism in the lower part of the machine, not seen in Fig. 1.

The type of bookbinding machine referred to handles a succession of books B, three being shown in Figs. 1—3, and the book being indicated also in other figures. The books are shown spaced apart and may be supposed to be advancing intermittently toward the right in Fig. 1, each book stopping at the position or station wherein it is to be operated upon, for example the middle book B in Fig. 1 having paused at the station at which the headband or other backlining element is to be applied. After a sufficient pause each book will again be advanced and the succeeding book brought into its place. As best seen in Figs. 4—7 each book is supported in the advancing or conveying means with its back uppermost. For example with a round back book the round back extends horizontally along the upper side, above the conveying means and exposed to the operating mechanism, while the body of the book is held vertical by the advancing means. The mechanism herein illustrated is particularly designed for applying the headbanding component to the book, and each book before arriving at the headbanding position is supposed to have received a coating of glue, meaning any suitable adhesive, indicated by the layer G in Fig. 6. Each headband H may consist of a doubled over piece of fabric, with a cord inserted in the fold, so as to produce an ornamental bead, which bead is herein utilized in the guiding of each headband strip H' to the point where individual headbands are to be severed and applied to the glued back of the book. The headband strip or supply H' is clearly shown in Figs. 2, 3 and 4 as coming from a supply point or points as will be more fully described.

The mechanism of this invention is shown as mounted above a base casting or frame piece 14, which may be a running member extending the entire length of the machine and giving support to various mechanisms, this base piece in turn being fixedly supported above the usual bed or foundation of the machine, omitted herefrom. Near the back edge of the base 14 is an upstanding bracket 15 giving support to various parts of the mechanism, this showing best in Figs. 2 to 5.

Beneath the base 14 is shown what may be termed the main shaft 17, which may extend the entire length of the machine and serve for operating various mechanisms, and with suitable connections to cause the step by step advance of the successive books along their horizontal path of travel. The main or

operating shaft 17 is shown as carrying a series of six cams as best seen in Figs. 1, 2 and 4. These cams will be enumerated at this point and referred to later in connection with the trains of mechanism actuated by them. The first or lefthand cam 18 on the shaft 17 cooperates with a follower 77 to control the pneumatic or suction action by which the holding and releasing of headbands is effected. The second cam 19 cooperates with a follower 66 to cause the actuation or swinging of the headband receiver or table on which the headbands are deposited by the feeding and severing means. The third cam 20 controls or brings about the intermittent feed of the headband strip into severing position above the receiving table in cooperation with the follower 172. The fourth cam 21 cooperates with a follower 111 for the purpose of controlling the movements to and from the book of the carriage and applicers which take the headbands from the tables and carry and apply them to the backs of the books. The fifth cam 22 cooperates with a follower 46 for the purpose of applying and releasing a certain book clamping device that applies pressure to hold each book back firmly in place during headbanding. The sixth and last cam 23 cooperates with a follower 230 having a train of connections for operating the severing device or shearing blades to sever the successive headbands. The several cams and their attendant trains of mechanisms are arranged in proper cooperative timing to effect the feeding, severing, receiving and applying of the headbands in coordination with the application and release of suction, the clamping and releasing of the books and the intermittent travel of the books into and from headbanding position.

Referring next to the book advancing means this may be of the type shown in said prior patents wherein the book is slid along under proper guidance and thereby caused to travel from station to station. Thus, behind the book is shown a back guide or rail 25 in the nature of a vertical wall and opposed to it a similar front guide rail or wall 26, these two guide walls enclosing a book groove or chute between them and extending longitudinally for the full length of the machine. Directly beneath and supporting the book B is shown an under rail 28 with convex upper side, and as usual adjustable vertically to receive the concave edges of books of varying width. As in said patents the front book guide wall 26 may be adjustable to and from the other or fixed guide wall 25 to accommodate books of varying thickness, and in connection therewith the under rail 28 may be adjusted to a central position.

The successive books may be pushed or thrust forward by a series of traveling pins 30 attached to a sprocket chain 31 guided in the back guide wall 25, the pins being suit-

ably spaced on the chain and projecting across the groove or chute between the guide walls, so that each pin can advance an individual book and bring it in a step by step manner to the successive stations. The chains and pins may move to the right, the return stretch being shown below the rail 28. On top of each guide wall 25 and 26 is shown an attached extension wall 27, enclosing the projecting part of the book except where interrupted to accommodate the clamp device to be described.

The back edge of the book B projects above the guide walls 25 and 26, and it is desirable during the headbanding operation to compress or steady the book against deflection. For this purpose a clamping means is indicated in the form of a back clamp member 33 and opposed to it a front clamp member 34, these members having elongated opposing faces and the member 34 being adapted to be moved toward the member 33 after each book comes to rest at the headbanding station, so as to contact and hold the book rigid during headbanding. An adjustment for clamp member 33 is best shown in Fig. 7 wherein a screw 36 affords up and down adjustment in relation to a double shouldered block 37 which in turn is adjustable forward and backward and held by a screw 38.

The connections for reciprocating the front clamp member 34 are best seen in Figs. 3, 4 and 9. The forward extending stem of the clamp member 34 is shown as connected by back toggle links 40 with front toggle links 41 pivoted upon a double bracket 42 mounted on the front guide wall 26. In order to straighten the toggle and thereby operate the clamp the middle joint of the toggle is shown connected by a long link 43 with the front end of a cam lever 44 having its rear end pivoted upon a fixed axle 45 and at an intermediate point having a cam roll 46 bearing upon the periphery of the cam 22 on the main shaft, as seen also in Figs. 1 and 2. A strong spring 47 opposes the cam and affords a limited degree of compression on the book. The timing of the cam causes each book to be clamped while pausing at the headbanding station, and to be released at the completion of the operation so as to permit its forward travel.

Each headband as it is severed is arranged to be received upon a table or retractable support 50 best shown in Figs. 3 to 5. The two receiving tables are symmetrically arranged and are indicated in their retracted position, being mounted upon a carriage which can be swung toward the back to bring the receiving tables to positions directly above the ends of the book. The carriage for the headband tables 50 may be a built up structure comprising the following elements. A cross bar or head 51 is shown at each end, each carrying one of the tables 50. These cross bars

are slidable longitudinally along rear and front axle members 52 and 53 which in turn are interconnected by end bars 54 forming with them a rigid square frame or carriage. Turning freely at the middle part of each end bar 54 is a threaded shaft 55 engaging threads in the cross bars 51, each shaft having a head or handle 56 by which it may be turned, thus to adjust longitudinally the corresponding cross bar, thereby permitting each receiving table 50 to be initially set according to the length of the book.

The carriage so described is swingingly supported at the top ends of four vertical arms 58 and 59 connected to the axles 52 and 53 respectively. The lower ends of the arms 58 are mounted on an axle 60, and the lower ends of arms 59 on axle 61, the axles 60 and 61 being supported in double brackets 62, one at each end of the system. An axle 63 at a midway point in the height of the front arms 59 does not represent joints but only a means to rigidify the system of supporting arms. The described system may be swung in timed relation to the other mechanisms through a cam lever 64, 65 fulcrumed on axle 61, and the upper arm 64 of which is connected to a stud or short axle 68 as best seen in Figs. 3 and 9, its other arm 65 extending back and downwardly (Fig. 4) and carrying a cam roll or follower 66 resting upon the cam 19. A spring 67 is arranged to move forwardly the carriage and receiving tables in opposition to the cam.

Each of the receivers or tables 50 is in the nature of a temporary holder, from which the received headband is taken by a headband applying device and subsequently applied directly upon the book after the retraction of the table from above the book. Each applying device may consist of two parts, a headband holder 70 preferably of the suction type, and a headband shaper 90 cooperating therewith to bend or shape down one or both ends of the headband around the sides of the convex back of the book.

Referring first to the suction holders 70 each of these may consist of a narrow bar or slide movable toward and from the book, in this case vertically downward and back. Fig. 5 best shows the relative arrangement, and the details of construction are shown in Figs. 6 to 8. Each suction holder or bar 70 is formed with interior suction passages 72, of which there may be two symmetrically spaced as seen in Figs. 7 and 8 to afford an efficient hold upon the headband strip H. The top end of the suction holder bar 70 is enlarged as a head 73 and at the top of this is coupled a flexible pipe or pneumatic hose 74 which, as seen in Figs. 1 and 4, extends over to the back, the two flexible pipes from the respective holders being brought together by a suitable coupling from which extends a suction pipe 75 controlled by a pneumatic

valve 76 shown in Figs. 1 and 2. The construction of the valve will be understood without illustrating details. It may be suitably connected with a suction fan or compressor so as to draw air from the pipe 75 in one position and to connect said pipe with the atmosphere in another position. The valve is shown as having a slide 77 for effecting the two stated adjustments, and this slide 10 may also constitute a follower cooperating directly with the cam 18 on the main shaft, the cam thrusting the slide down at one point in the cycle to connect the pipe with the compressor and thus apply suction, and letting it 15 up at another time to connect the pipe with the atmosphere and release suction.

Each of the suction holders or bars 70 is shown as slidable vertically within a block 78 as best seen in Fig. 5. The block 78 is 20 a part of a vertically moving carriage, the block being attached by a screw 79 to a carriage bar 80, which is in the nature of a bridge, extending across to the back side of the apparatus where it is fitted to receive 25 downward and upward movements. At its forward end the carriage bar 80 is formed with a longitudinal slot 81 permitting the block 78 to be initially adjusted to exactly correct position on the carriage. Fitted into 30 a lug on the head 73 of the holder bar is shown a stop screw 84 adapted to come down upon the block 78 in the descent of the holder, thus limiting its descent relatively to the carriage. Beneath the block 78 the holder bar 35 is shown formed with a stop 85 which limits the relative lifting movement of the bar in the carriage. A spring plunger 86 is arranged to press downwardly and maintain the bar normally in the position shown, with 40 the top 84 contacting the block. This plunger may extend upwardly from the stop lug 85 and into a recess within the block 78 where it is acted upon by a spring 87 thrusting downwardly thereon.

45 Referring next to the shaping device, comprising one or two opposite portions or wings 90, as best seen in Fig. 5, each of these is shown in the form of a vertical bar sliding closely adjacent to the hollow bar 70 constituting the suction holder. The narrow ends or faces of the shaper bars are beveled inwardly, and these ends normally stand relatively higher than the extremity or nozzle end of the suction holder, so that when the 50 assembly descends to the headband and later to the book the suction holder will arrive first, thereby positioning the headband, the shaper wings following as the holder relatively yields, these three parts together 55 forming substantially to the size and curved shape of the headband as finally attached on the book.

For constructional purposes each of the shaper bars 90 is shown as offset away from the holder bar and continued as a vertical

shank 92, which shank may have an enlarged head 93 at its top end, the shank sliding vertically within a recess in a block 94. The two blocks 94 for the two shaper bars are attached by screws 95 to the bridge bar 80 in 70 properly adjusted position with the block 78 between them. The head 93 of the shaper bar is provided with a stop screw 97 contacting with the block 94 for determining the normal position of the bar. At a point below the block each bar is provided with a stop lug 98 limiting the relative upward movement of the bar in the block, and each lug 98 may have extending upwardly from it a plunger 99 passing into the block 94 and 75 therein acted upon by a spring 100 tending to depress the bar into the normal position shown. By this arrangement the holder bar and the two shaper bars are relatively yieldable as the carriage with blocks descends in 80 the applying operation. If desired the spring 87 resisting the yielding of the holder bar may be lighter than the springs 100, so that the shaper bars will deliver a greater pressure upon the headband to bend and shape it 85 around the book.

90 Each of the carriage bars or bridges 80 is shown as a horizontal bar extending rearwardly at an elevated point and this bar constitutes part of a descending and rising carriage by which the headband applicer is moved down and lifted. To the rear of the blocks at the front end of each bar, the bar is shown as extending between a pair of guides 102 which as will be explained later 95 are connected with a slidable carriage longitudinally adjustable for variations of book length and serving to adjust the applicers and other elements accordingly. At its rear end each carriage bar 80 is screw-attached 100 to the top side of a sliding block 103 shiftably mounted upon but secured by set screw 104 to a longitudinal guide bar 105. By this arrangement when the screws 104 are 105 loosened, each of the carriage bars may be 110 adjusted longitudinally on the guide bar 105. The guide bar 105 is fitted for vertical movement as follows. It is carried at its right and left ends by upward projections 115 at the two ends of a horizontal extension member 106 provided at the top end of a slide 107 having a vertical dovetail engagement with the rear side of the fixed frame bracket 15, so that the up and down sliding 120 of the slide 107 carries with it the guide bar 105 and both carriage bars 80 and both applying mechanisms. The slide 107 is shown 125 as provided with an adjustable stop screw 108 adapted to come down upon the bracket 15 and thus limit the downward movement of the system. Below the slide 107 extends an actuating link 109, the lower end of which 130 is pivoted to the rear end of a cam lever 110 which lever carries a cam roll 111 engaging on the cam 21, the front end of the lever 135

being fulcrumed on an axle 112. By this arrangement the cam, opposed by gravity, operates at the proper times to move or lift the described system to the normal or retracted position as shown, and at other times to allow it to move or descend so as to bring the headband holder and shaper first into position to take a headband from each of the tables 50 and thereafter to carry such headbands to and apply and shape them upon the book.

Next will be described the two longitudinally adjustable slide carriages 113 and 113^a, arranged at the left and right respectively, each carrying a pair of the slotted upstanding guides 102 already mentioned by which the headband applying devices are shifted longitudinally; and each of the carriages also supporting or giving longitudinal adjustment, as will be described, to the headband feeding devices and to the headband severing devices, to adapt all of them to variations in length or position of the books. The location and construction of the longitudinal carriages 113 and 113^a are best seen in Figs. 2, 3 and 5.

Each longitudinal carriage, at its lower rear part, is formed with a slidable base or longitudinal bar 114 or 114^a from which depend feet 115 and 115^a supported and guided in grooves in longitudinal brackets 117 and 117^a and held firmly in place by holdown plates 118. The brackets also carry longitudinal shafts or bolts 119 or 119^a which are threaded to engage with depending nuts or lugs 120 or 120^a, so that by manually turning the heads of the shafts, or either of them, the respective carriages are adjusted longitudinally of the machine to accommodate the applying, feeding and severing devices to variations in length of book. Each carriage 113 or 113^a extends upwardly to a substantial extent, its upper portion being split into front and back sides 121 forming between them a guiding recess 122 to receive the journal blocks 147 of the upper feed shaft to be described, the top of each carriage being capped by a top plate 123. In the adjusting movements of each longitudinal carriage it is held steady in its position by the elongated guided foot 115 and by the engagement of its depending lug 120 with the threaded shaft 119 and by the sliding engagement of the lower front corner 124 upon the fixed back guide wall 25; and it may be secured tightly after adjustment by set screw or otherwise. Further configuration and connections of the longitudinal carriages will be hereinafter referred to.

Describing next the supplying and feeding of headbands, the headbands strip H' is shown as carried in rolls on a pair of supply reels or spools 130, which may have a greater width and capacity than shown, and which are located to supply the material to the two ends

of the book. Referring particularly to Figs. 2-4, the two spools are shown as mounted loosely upon a common axle 131 removably supported in a pair of rear brackets 132. From the upper side of each roll the strip is shown traveling at a frontward upward slant to an idler roller or pulley 133, around said pulley and thence down and around an under pulley or idler 134 from which the strip delivers substantially horizontally frontwardly toward the severing and applying point. The idler pulleys or guides 133, 134 for each strip are shown mounted on a special bracket 135 extending rearwardly from the longitudinal carriage 113 or 113^a, so that these guiding pulleys partake of the longitudinal adjustments. Obviously the supply spools also might be adjustable longitudinally either automatically or manually. Adjacent one of the idler pulleys 133 is shown in Fig. 5 a friction device 136 of spring character bearing upon each headband strip so as to impose drag or friction thereon to maintain the strip taut between that point and the feeding devices. The pulleys 133 and 134, and other guiding and feeding parts, may be constructed with grooves at one side to conform to and receive the bead which is provided at one side of the headband strip, thus aiding in the correct guiding and feeding of the strip.

From the guide pulleys the headband strip passes frontward between upper and lower guide plates 138 and 139, one or both of which are interiorly recessed to form a guide passage for the strip. These guide plates preferably extend beyond the feeding point, having recesses to accommodate the feeding rolls, and being continued frontwardly to where they deliver the strip to the receiving tables and severing devices. The upper guide plate may be yieldable to irregularities in headband material by means of spring devices 141 shown near each end in Fig. 5.

The headband strip feeding devices comprise for each strip an under feed roll 143 and an upper feed roll 144 both of which are roughened or knurled, these rolls extending into recesses in the guide plates 138 and 139 and cooperating in imposing feeding pressure upon the strip, the rolls being rotated to thrust the strip frontwardly. This construction is best seen in Figs. 2, 3 and 5.

The two upper feed rolls 144 are both mounted on a common shaft 146 rotating in journal blocks 147 accommodated in the recesses 122 already mentioned formed between the upward extensions 121 of the longitudinal carriages 113 and 113^a. Each block may slide upwardly guided in its recess but is held resiliently down. A threaded rod 148 is shown spaced above the block 147 and threaded in the carriage top piece 123. Surrounding the rod is a spring 149 pressing down on the block, with a regulating nut 150

70

75

80

95

100

105

110

115

120

125

130

to adjust the resilient pressure of the upper feed rolls upon the material. The rod acts as a stop to the rise of the block and as such may be vertically adjusted by rotating it, a lock nut 151 being shown for fixing its adjustment. The left end of the upper feed shaft 146 may be extended and provided with a hand wheel 152 (Fig. 3) by which the shaft and feed rolls can be manually rotated for feeding strip at will and for initially threading the material into the machine.

The upper feed shaft 146 may be rotated through a gear 153 carried upon it and meshing with a gear 154 which in turn is carried on the lower feed shaft 156 which carries the lower feed rolls 143, the gears and shafts being intermittently rotated to afford feed at the proper points of time. It will be understood that the several feed rolls have a tongue and groove or spline engagement with their respective shafts, so that all the rolls are compelled to rotate in unison while permitting longitudinal adjustment. In the case of the under feed rolls, as seen in Fig. 3, these may be integral with bearing sleeves turning with journals or bearings 157 mounted in the longitudinal carriages 113, 113^a, and the upper feed rolls may be similarly mounted in their journal blocks; so that longitudinal adjustments of either of the carriages is communicated to the feeding rolls as well as the strip guiding means.

For intermittent rotation of the feed rolls, to advance the headband strip to the proper extent prior to each severing and applying action the following devices are shown. Fast on the lower shaft 156 is mounted the driven member 160 of a clutch of which the driving member 161 turns loosely on the shaft and is connected with a gear 162. The clutch is adapted to drive in forward direction only and may be of the well known ball clutch type with rolling elements that wedge the clutch members into engagement on the forward actuation but allow the driven member to stand idle on the return movement of the driving clutch member. The driving member 161 is shown as oscillated to an adjustable degree through a toothed vertical rack 164 meshing with the gear 162, the rack being mounted upon a sleeve 165 having means for reciprocating it as will be described.

The sleeve 165 which effects the oscillation of the feed gears surrounds a rod 167 which, as will be described, is extended and connected to the feed operating cam. For a particular purpose the sleeve however is arranged to have a slight vertical play or looseness on the rod, so that the rod can reciprocate to a very slight extent in a vertical direction without causing movements of the sleeve and rack. This condition is indicated by the provision at the top of the rod of an enlarged head 168, the lower side of which is shown 65 contacting the upper side of the sleeve, but

at times is spaced slightly above it. At its lower end the rod 167 is shown connected to an extension rod 169, for example by a connecting pin, the top of the lower rod being sufficiently enlarged to form a support on which the sleeve rests. The extension rod is carried downwardly and through the machine base 14 and the lower end of the rod is shown connected by a link 170 with a cam lever 171, this cam lever being fulcrumed at the front side of the machine on the axle 112 and carrying near its center a follower or roll 172 which engages in the groove 20 of the feed cam. Contrary to the other cams the cam 20 therefore operates to pull down on its follower. This action is opposed by a spring 174 arranged under compression surrounding a rod 175 pivoted to the free end of the cam lever and with its lower end sliding through a bracket 176 which also confines the lower end of the spring. The tendency of the spring therefore is to thrust upwardly the rod 169, 167 and the rack 164 while the cam tends to draw them down, thus creating the reciprocation to operate the headband feed. It will be noticed that while the cam roll 172 operates in a groove in the cam, this groove is of such width that the cam lever is not bound to follow the cam surface but may at any time be thrust or held downwardly against the pressure of the spring, this feature permitting an adjustment of the length of reciprocation and therefore the extent of headband feed.

The adjustment of feed and therefore of the length of the headbands may be effected by the following devices. Mounted near the lower end of the extension rod 169 is a collar or stop 178 shown in its lowered position in Fig. 5. When the cam 20 permits the spring 174 to move the rod upwardly this brings the stop 178 into contact with a complementary stop member 179 shown in the form of a sleeve surrounding the rod. The distance of movement of the stop collar before it strikes the stop sleeve represents the extent of feed, and this may be adjusted by relative adjustment of one or both of the stops. A convenient manual adjustment may be effected as follows. The stop sleeve 179 is shown as slidable within a bearing block 180 on the frame standard 15. The front side of the sleeve is formed into a rack 181 and this rack is engaged by a pinion 182 mounted on a stud shaft 183 which takes its bearings in a pair of frontwardly extending ears 184 which ears are slit and are provided with a clamping screw 185 to draw them together. As seen in Figs. 2 and 5 the left end of the shaft 183 carries a hand wheel 186. By this arrangement the turning of the hand wheel effects the vertical adjustment of the sleeve, and one or the other of these parts may be calibrated to indicate the length of feed, and after such adjustment the screw 185 will be turned to clamp and lock the pinion shaft and

thus hold the sleeve in the desired position. For any given adjustment the operation is that the cam 20 throws down the rod 169 in each cycle to its lowest point and then lets it up under pressure of the spring 174, the rise continuing until the stop collar 178 meets the stop sleeve 179. Subsequently the rod will again be moved down and let back to the same adjusted position.

20 For the purposes of a device to detect the presence or absence of a book and to prevent feed of headband in the latter case the rod 169 is shown as enlarged and threaded at 188 at its upper end, this threaded portion 25 being engaged by a threaded sleeve or nut 189 having a head or flange 190 by which it can be turned to adjust it upwardly and downwardly, with a lock nut 191 for holding the adjustment. These parts cooperate with a 30 latch or finger 195 shown in the form of a depending lever having a notch 196 to engage the upper corner of the flange 190 at certain times, the lever being fulcrumed at 197 to a fixed frame part from which it depends. The 35 latch lever 195 is shown in the release position in Fig. 5, but when shifted to holding position as in Fig. 4, this operates to hold down the rod 169, 167, and prevent feeding movements. As will be explained this occurs only when a book is missing, the presence of each book serving to swing the latch lever away from holding position, thus releasing the rod for its up and down reciprocation and feed. On the return or down 40 movement of the rod the flange 190 will act against the inclined surface 198 of the lever so as to cam it frontwardly and permit the flange to pass by to its illustrated position.

When the rod 169 is in its completely lowered position the upper surface of the flange 190 will stand slightly lower than the horizontal surface of the notch 196. This clearance is important else the friction pressure of the flange in the notch would interfere 45 with the frontward retraction of the lever. From this fact appears the importance of the slight play already described between the upper rod 167 and the sleeve and rack surrounding it. Assuming that several books 50 in sequence are missing the latch lever will remain in its holding position and the rod will vertically reciprocate through a very small movement. Due to the gap below the rod head 168 this movement is inoperative 55 to effect even a slight feed of headbands, otherwise when the machine is running without books the strip would be fed forward a very small amount in each cycle and small slivers of headband would be chopped off by 60 the severing means.

The feeling or detecting of the book and the control thereby of the latch finger 195 may be as follows. A feeler 200 is shown pivoted at 201 and taking the form of a light 65 arm or finger extending through a slot 199

in the back guide wall 25. This feeler is lightly pressed into the slot and book groove by a light spring 202, so that each book can readily thrust the feeler out to the position shown in Figs. 3-5, whereas in the absence 70 of a book the spring throws the feeler in and effects the control as will be described. The control point is one book space ahead of the headbanding station so that when the book which has operated upon the feeler subsequently comes to position the headband will have been properly fed for application thereto, but in the absence of the book the feed will be prevented.

The light feeler spring 202 surrounds a light rod 203 which rod in turn is slidable through a bar 204, the spring being under light compression between the feeler and the bar. The bar hangs vertically from the rod and is acted upon not only by the light spring 80 202 but also by a heavier spring 205 which exerts a tension pull upon the bar. The bar in turn is swivelled at the left end of a control lever 207 which is fulcrumed at 208 on the rear guide wall 25 and extends beyond 90 the fulcrum at a rightward rearward slant to where it has an offset 209 having a pivotal engagement with the latch finger 195. The springs are so related that when no book is present and the light spring is relaxed the 95 left end of the control lever 207 will stand frontward while its right end stands rearward, the pull of the heavy spring 205 causing the latch finger 195 to swing to its holding position as shown in Fig. 4, thus preventing feed. When a book is present the feeler swings back to the Fig. 5 position thus putting the spring 202 under compression. This changes the balance and the heavier 100 spring 205 is caused to stretch slightly and the control lever 207 swings sufficiently to retract the latch finger frontwardly so that its notch 196 will clear the flange 190 of the reciprocating feed rod 169. The spring 205 in one sense holds the control lever in a normal position in a resilient manner so that the lighter spring operated by the book is able to throw the parts out of holding position, and thus permit the feed of headband material to the book.

110 The severing of the individual headbands H from each of the strips H' may be effected by the following disclosed mechanism. An under blade 215 may be relatively fixed, and cooperating with it is a movable upper blade 216. These are both mounted upon a fixed member or block 217 attached adjustably by set screws 218 upon the longitudinal carriage 113 or 113^a. The swingable upper blade is mounted on the block by a spring pivot 220. Each upper blade 216 carries an operating pin 221, and these two pins are engaged by a horizontal bar 222 provided with slots 223 in which the pins are entered. When the actuating bar is moved downwardly this op- 125 130

erates both severing devices at once to shear the strips. The right and left ends of the bar 222 are shown mounted at the upper ends of parallel vertical slides 224, all as shown in Fig. 1.

5 The downward and upward movements of the slides and actuating bar may be effected as follows. Each slide moves vertically in a guide 225 best shown in Fig. 2. From each 10 slide extends a link 226 to the front extremity of a rock arm 227, shown also in Fig. 4. The two rock arms 227 are mounted on a common shaft 228 from which extends a cam lever 229 carrying a roller 230 resting on the 15 periphery of cam 23. The cam is so timed as to depress the actuating bar and operate both severing devices immediately after the headband strips have been fed frontwardly upon their respective receiving tables 50.

20 The following device may be employed to register each headband longitudinally to its proper position on the book and at the same time to square it accurately to the width of the book. See Figs. 1 and 4-8. The registering member is shown in the form of a lever 234 or 234^a extending upwardly from the registering point and having an upper arm or extension 235 beyond its pivot 236. This transverse pivot permits the lever to 25 swing longitudinally to bring its lower or registering end up to the book and headband, so that the registration of the headband will be directly from the book. The lever is shown as pivoted upon a bracket 237 which 30 is rigidly attached to the left side of the middle carriage block 78, this being the block that carries the suction holder 70 and descends along with other parts in the applying action. By this arrangement when the 35 carriage 80 moves downwardly to apply the headband it carries with it the registering lever.

The registering lever 234 at its lower end, 40 as best seen in Figs. 5 and 6, is provided with two contacts 239 and 240, the contact 239 being in the nature of a feeler intended to 45 contact the end of the book and thus determine the registering position of the lever, while the contact 240 is an adjuster adapted 50 to contact the headband as it is being applied to the book, and to register, aline and square it to the back of the book, and adjust it longitudinally so that the bead of the headband will overhang the book to the desired 55 extent. In the finished product the relation of the headband to the book is determined by the relation of the feeler 239 to the adjuster 240, and this relation may be varied at will by the following means. The feeler 60 239 is shown as having a threaded shank 242 engaging in a threaded aperture in the lever 234, so that the feeler can be adjusted relatively to the adjuster by rotation, the adjustment being secured by a set screw 243. 65 The headband adjuster 240 is shown pro-

vided with a shank 245 extending along the lever 234 and slotted to receive a set screw 246, so that the adjuster can be set vertically to the position of the headband.

The registering operation is that each of the two levers 234 and 234^a descend in retracted or outswung position, so as to clear the book and headband, and thereupon swing inwardly until the feeler contacts the book, the adjuster at the same time contacting, 70 alining and positioning the headband. Preferably a spring 248 is employed to swing the lever in, this spring acting outwardly on the upper arm 235 of the lever. The retracting motion may be effected by cam action by reason of the vertical movement of the registering lever, its upper arm having a vertical edge or surface 249 and thereabove an inclined edge 250. These cam surfaces 249, 75 250 cooperate with a cam roll 252 adjustably mounted in a slot 253 of a bracket 254 which is rigidly attached by set screws 255 to the carriage 113 or 113^a (or to the knife block 217 fixed thereon) so as to partake of longitudinal adjustments of the carriage made to accord with variations of book length. The cam and roller are so relatively timed, as shown, that as the lever descends during the headband applying action the roll is in contact with the vertical surface 249 until just before application, when the inclined surface 250 comes opposite the roll thus permitting the spring to swing the lever, after the feeler 239 has descended to a position opposite the end of the book. The final descending movement permits the feeler to be swung into contact with the book, the adjuster at the same time contacting and adjusting the headband just before or just as it is applied and pressed against the glued back of the book.

In describing above the respective mechanisms it is thought that the operations thereof and the relative operations and timing have been sufficiently set forth without requiring a summary of the entire action of the machine. The two headband strips are fed frontwardly over the advanced receiving tables and at the completion of the feed the severing devices cut off the individual headbands, which thereupon lie upon the tables. The respective applicers descend, each having its suction holder in advance of its shaper. The applying cam is so shaped that the applicers pause when the suction holders have descended to the headbands. This permits the suction to take secure hold of the headbands before the tables retract frontwardly, after which the descent is continued until the headbands are applied and shaped to the previously glued back of the book.

There has thus been described a bookbinding machine or mechanism for applying booklining components or headbands to books, embodying the principles and attain-

ing the advantages of the present invention. Since many matters of combination, arrangement and construction may be variously modified without departing from the principles of the invention, it is not intended to limit the invention to such matters except to the extent set forth in the appended claims.

What is claimed is:

10 1. In a bookbinding machine mechanism for automatically applying backlining components to the glued backs of books, comprising opposite guide walls between which the book may advance edgewise to and from applying position with its back exposed and having means to adjust them for variations of book thickness, a book compressor or bar movable relatively to said walls to press upon and release the exposed part of the book, spring means to engage the compressor with the book during application of a component, and timed means to retract the compressor during advance of the book.

2. A bookbinding machine as in claim 1 and wherein the compressor is movably mounted upon a wall to adjust therewith, a transverse toggle device pressing the compressor toward the book also mounted on said wall, the spring means arranged to straighten the toggle to effect compression, and cam means to bend the toggle to release the book.

3. In a bookbinding machine mechanism for automatically applying backlining components to the glued backs of books, comprising means for advancing the book edgewise to and from applying position with its back exposed upwardly, a receiving table above the book, means for feeding components to the table to rest temporarily thereon, means to remove each component from the table and subsequently apply it to the book, a carriage at one side of the book position from which the table projects above the book, a linkage supporting the carriage to swing inwardly and retract, and timed means to swing and retract the carriage and table in coordination with the feeding and applying means.

4. In a bookbinding machine mechanism for automatically applying headbands to the glued backs of books, comprising means for advancing the book edgewise to and from applying position with its back exposed upwardly, two receiving tables one above each end of the book, means for feeding headbands to the tables to rest temporarily thereon, means to remove the headbands from the tables and subsequently apply them to the ends of the book, a carriage at one side of the book position from which both tables project above the book, and timed means to shift and retract the carriage and tables in coordination with the feeding and applying means.

5. A bookbinding machine as in claim 4

and wherein one or both of the tables are longitudinally adjustable on the carriage for length or position of book.

6. In a bookbinding machine mechanism for automatically applying headbands to the glued backs of books, comprising means for advancing the book edgewise to and from applying position with its back exposed upwardly, means for feeding headbands, and means for applying the fed headbands to the book comprising a holder and a shaper, a vertically movable carriage on which the holder and shaper are adjacently mounted, the shaper normally retracted relatively to the holder, with resiliently yielding means in the mounting of the holder, and timed means causing the descent of the carriage to apply and shape the headband to the book.

7. A bookbinding machine as in claim 6 and wherein the shaper also has a yielding mounting in the carriage but with stronger resilience than the holder, and the carriage is caused to descend by gravity applying the weight of the parts to the holder and shaper.

8. A bookbinding machine as in claim 6 and wherein the shaper consists of opposite shaping parts, with the holder between them, and the three independently yieldingly mounted on the carriage.

9. A bookbinding machine as in claim 6 and wherein the carriage, holder and shaper are duplicated at the two ends of the book, with means for relatively adjusting longitudinally one or both of the carriages.

10. A bookbinding machine as in claim 6 and wherein the holder and shaper are transversely adjustable on the vertically movable carriage, while the latter is supported on a longitudinally adjustable carriage.

11. In a bookbinding machine mechanism for automatically applying headbands to the glued backs of books, comprising means for advancing the book edgewise to and from applying position with its back exposed upwardly, means for feeding headbands above the two ends of the book, separate devices for applying the fed headbands to the ends of the book, separate vertically movable carriage on which the respective applying devices are mounted, separate longitudinally adjustable carriages on which the respective vertically movable carriages are mounted, separate means for adjusting the longitudinally adjustable carriages according to the positions of the respective ends of the book, and separate means for feeding headbands also mounted upon and adjustable with the respective longitudinally adjustable carriages.

12. In a bookbinding machine mechanism for automatically applying headbands to the backs of books, comprising means for advancing the book edgewise to and from applying position with its back exposed, means for applying headbands to the book, means

for severing headbands from a strip, and means for feeding headband strip comprising feed rolls, a one-way clutch, a reciprocating rack, a cam moving the rack in one direction, a spring moving it in the opposite direction, a stop member moving with the rack, a stop member adjustable along the line of reciprocation, a rack on the adjustable stop, a pinion for adjusting the stop rack to alter the extent of feed, and means for locking the pinion and rack when adjusted.

13. In a bookbinding machine mechanism for automatically applying backlining components or headbands to the backs of books, having means for advancing the book edge-wise into and from applying position with its back exposed, and mechanism for feeding strip to be severed and applied to the book, comprising feed means or rolls, a reciprocating feed member or rod having connections for communicating feed motion in one direction only to the feed means or rolls, a resilient means or spring to advance the feed rod, and a timed means or cam to retract it, a projection on the feed rod, and a latch cooperating therewith to latch the rod at or near retracted position to prevent feed movements, a detector or device feeling the presence or absence of a book, and connections from the detector to the latch whereby in the presence of a book the latch is rendered inoperative, and the feed thereby operative.

14. A bookbinding machine as in claim 13 and wherein the detector comprises a finger tending to enter the path of the book and the connections to the latch comprise a lever, a spring tending to hold the lever yieldingly in position with the latch operative, and a relatively lighter spring between the finger and lever, whereby when a book displaces the finger a force is transmitted shifting the lever to render the latch inoperative.

15. In a bookbinding machine mechanism for automatically applying backlining components or headbands to the backs of books, having means for advancing the book edge-wise into and from applying position with its back exposed, and mechanism for feeding strip to be severed and applied to the book, comprising feed means or rolls, a reciprocating feed member or rod having connections for communicating feed motion in one direction only to the feed means or rolls, a resilient means or spring to advance the feed rod, and a timed means or cam to retract it, a projection on the feed rod, and a shiftable latch cooperating therewith to latch the rod near retracted position to prevent feed movements, a detector or device feeling the presence or absence of a book, and spring connections from the detector to the latch whereby in the presence of a book the latch is shifted from latching position; the latch being so positioned that the latching position of the

rod is slightly removed from its full retracted position whereby the full retraction of the rod frees the latch for withdrawal by the detector connections.

16. In book headbanding mechanism, a reciprocating rod or member with connections therefrom to feed the headband material intermittently to book position, timed means to advance and retract the rod with a yielding element therein permitting the rod to be restrained in retracted position, a restrainer or latch arranged to hold the rod in retracted position and thus prevent feed, and a feeler operated by the presence of a book, with connections to the latch for withdrawing it to permit reciprocation of the rod and feed of material.

17. In book headbanding mechanism, a reciprocating rod or member with connections therefrom to feed the headband material intermittently to book position, timed means to advance and retract the rod with a yielding element therein permitting the rod to be restrained in retracted position, a restrainer or latch arranged to hold the rod in retracted position and thus prevent feed, and a feeler operated by the presence of a book, with resilient connections to the latch for withdrawing it to permit reciprocation of the rod and feed of material; the retracted and latched positions of the rod being slightly different, whereby upon full retraction the latch is freed to be withdrawn by the resilient connections from the book feeler.

18. A mechanism as in claim 17 and wherein in the connections from the rod to the headband material is a slight lost motion sufficient to offset the vibration of the rod between retracted and latched positions, whereby such vibration will not be transmitted as successive short feed actions in the absence of books.

19. In book headbanding mechanism, means for applying a headband to a book, and a movable registering member or lever coming into operation as the headband is being applied, said member having a feeler coming into contact with the book end, thus positioning the member, and an adjuster thereby caused to contact the headband, square it to the book and adjust it to overhang the book end by a predetermined amount; the feeler having an adjustable mounting upon the member to vary the registering position of the member relatively to the book and thereby the position of the headband upon the book.

20. In book headbanding mechanism, means for applying a headband to a book, and a movable registering member or lever coming into operation as the headband is being applied, said member having a feeler coming into contact with the book end, thus positioning the member, and an adjuster thereby caused to contact the headband,

square it to the book and adjust it to overhang the book end by a predetermined amount; the registering member being mounted to move bodily toward the book with the headband applying means, and the adjuster being adjustably mounted on said member for setting it to contact the headband.

5 In testimony whereof, this specification has
10 been duly signed by:

EUGENE R. SEITER.
